UNITED STATES PATENT OFFICE.

JACK A. PORTER, OF HOATH, SASKATCHEWAN, CANADA.

PLOWSHARE.

1,362,137.

Specification of Letters Patent.

Patented Dec. 14, 1920.

Application filed November 1, 1919. Serial No. 334,933.

To all whom it may concern:

Be it known that I, JACK A. PORTER, a subject of the King of Great Britain, residing at Hoath, in the Province of Saskatchewan and Dominion of Canada, have invented certain new and useful Improvements in Plowshares, of which the following is a specification.

This invention relates to plowshares, and 10 the object thereof is to provide a quickly detachable share, in which there are no small bolts to handle in the changing of the shares.

Another object is to provide means for 15 tightening or loosening a share so located as to be readily accessible.

With the foregoing and other objects in view, which will appear as the description proceeds, the invention resides in the 20 combination and arrangement of parts and in the details of construction hereinafter described and claimed, it being understood that changes in the precise embodiment of the invention herein disclosed may be made 25 within the scope of what is claimed without departing from the spirit of the invention.

In the accompanying drawings:

Figure 1 represents a side elevation of a 30 mold board and plowshare embodying this invention, said parts being separated and arranged in juxtaposition, parts being broken out and in section.

Fig. 2 is a similar view taken from the other side of the plow with the parts shown 35 assembled and partly in section.

Fig. 3 is a horizontal section taken on the line 3—3 of Fig. 2.

Fig. 4 is a vertical transverse section with the share shown in juxtaposition ready for 40 assembling in full lines and in assembled position in dotted lines; and

Fig. 5 is a vertical transverse section taken on the line 5—5 of Fig. 2.

In the embodiment illustrated, a mold 45 board 1 of ordinary construction is shown, and the share 2 for connection therewith is shown in Fig. 1 separated ready for assembling and assembled in Fig. 2. This share 2 is equipped on its inner face with longitudinally spaced hook-like lugs 3, positioned at an oblique angle, being inclined downwardly as is shown clearly in Fig. 4, and which form attaching elements connected as will be hereinafter more fully described.

Bolted to the inner face of the mold 55 board 1 adjacent its lower edge and pro-

jecting beyond said edge is a frog 4, being preferably in the form of a casting and provided on its inner face near its upper edge with guides shown in the form of apertured lugs 4^a and which are designed for the passage therethrough of connecting bolts 7 which will be hereinafter more fully described. Depending from the lower edge of the frog 4 in alignment with the lugs 4^a are slotted ears 5, the slots 5^a opening through the lower ends of said ears and being designed for the passage of the hook-like elements 3 carried by the share 2 when the share is to be assembled.

The bolts 7, two of which are shown, are of a length sufficient to extend transversely across the inner face of the mold board, being threaded at their upper ends and provided at their lower ends with flattened heads 7^a. These heads 7^a have slots 6, the upper and lower walls of which are beveled as shown at 6^a in Fig. 4, and through which are designed to pass the hooks 3 carried by the share.

Sleeves 8 are mounted on the bolts 7 above the frog 4 and are designed to rest on the upper ends of the apertured lugs 4^a, wing nuts 9 being screwed on the threaded upper ends of said bolts 7 above the sleeves 8 and 85 against which said nuts bear. It will thus be obvious that when these nuts 9 are screwed inward on the bolts 7 they will operate to move the bolts longitudinally upward, exerting a pulling tension or draw 90 on the hooks 3, which have first been placed in the slots 6 of the bolt heads 7^a. This tightening of the nuts, and upward movement of the bolts, securely locks the share to the mold board.

A brace rod 10 such as is ordinarily used, is arranged diagonally across the inner face of the mold board, being riveted at one end to the rear corner of the board, and bolted at its other end to the front end of the frog 4, said end being arranged in a plane at right angles to the body portion of the frog, the rod 10 having a foot 10^a through which passes the bolt 13 which connects it to the frog.

A lug 12 is carried by the inner face of the front end of the share 2, and is designed to enter an aperture 11 formed in the front end of the frog, as is shown clearly in Figs. 2 and 3, and operates to assist in securing the share to the mold board.

In the use of this invention, when it is de-

sired to remove the shares 2 for any reason, all that is necessary is to loosen the nuts 9 which will loosen the rods 7 to permit them to be moved downwardly into the position shown in Fig. 1 so that the hooks 3 of the share may be readily disengaged, and the share lifted off the mold board.

To apply a share 2, hooks 3 and lug 12 are engaged with the slots in the frog 4 and said hooks passed through the slots 6 in the bolt heads 7^a. The nuts 9 are then tightened to draw up on the bolts 7 and lock the share 2 securely to the mold board. It will thus be seen that no small bolts are employed for connecting the share to the mold board, the two large hand bolts 7 being the only bolts used.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

Having thus fully described my invention, what I claim as new and desire to secure by Letters Patent, is:

1. The combination of a mold board, a frog carried thereby and having guides on its inner face and slots alined with said

guides, bolts movable through said guides and having slots therein, a share having hooks for insertion through the slots in said frogs and bolts, and means carried by the bolts for locking the share in operative position.

2. The combination of a mold board, a frog carried thereby and having laterally offset guides on its inner face, and slots transversely alined with said guides, bolts movable through said guides and having slots therein with beveled upper and lower walls, a share having hooks for insertion through the slots in said frogs and bolts, and means carried by the bolts for locking the share in operative position.

3. The combination of a mold board, a frog carried thereby having laterally offset guides, slotted ears depending from the lower edge of said frog and alining with said guides, bolts movable through said guides and having flattened longitudinally slotted heads, sleeves mounted on said bolts above said guides, wing nuts carried by said bolts in advance of said sleeves, and a share having hook-shaped lugs on its inner face positioned to enter the slots in said ears and said bolt heads whereby the tightening of said nuts will operate to lock the share to the mold board.

In testimony whereof I affix my signature in presence of two witnesses.

JACK A. PORTER.
